UNITED STATES PATENT OFFICE.

JOHN WESLEY BARBER, OF NEWTON, MASSACHUSETTS.

FASTENER FOR SHOES, &c.

1,170,472.

Specification of Letters Patent.

Patented Feb. 1, 1916.

Application filed August 27, 1909. Serial No. 514,913.

To all whom it may concern:

Be it known that I, JOHN WESLEY BARBER, of Newton, in the county of Middlesex and State of Massachusetts, have invented certain new and useful Improvements in Fasteners for Shoes, &c., of which the following is a specification.

This invention relates to fastening devices especially adapted for the lacings of shoes, or other articles, which are secured by means of lacings, and my invention has particular reference to devices of this nature in which a roller is employed, around which the roller the lacing is passed.

15 One of the objects of my invention is to provide a lacing-holder which shall be strong and durable, similar in shape or style to the ordinary form of lacing hook, as well as simple, the housing for the roller being 20 so constructed that the roller cannot get out of place.

Another object of the invention is to provide a device of this character which shall have sides entirely open to facilitate the free 25 insertion and movement of the lacing.

Another object of the invention is to provide a device of this character having means whereby a durable and permanent coating is secured to upper or exposed portion of 30 the housing.

To these ends my invention consists in the construction and combination of parts substantially as hereinafter described and claimed.

35 Of the accompanying drawings,—Figure 1 is a perspective view of my device in one of its embodiments. Fig. 2 represents a section through the maximum area of the device, the roller being shown in elevation.

40 Fig. 3 is a detail sectional view, showing a modified form of trunnion structure for the roller. Fig. 4 is a view similar to Fig. 3, illustrating another form of bearing for the roller. Fig. 5 represents a section on line 45 5—5 of Fig. 2. Fig. 6 is a view similar to Fig. 2, but showing another structure of interlocking of the ends of the strip which forms the housing. Figs. 7 and 8 are detail 50 plan views of different forms of one end of the strip which is employed in constructing the form shown in Fig. 6.

Similar reference characters indicate the same or similar parts in all of the figures.

The entire device, with the exception of 55 the roller, is constructed preferably of a

single strip of metal of the necessary thickness to impart the requisite strength.

Referring first to Figs. 1, 2, and 3, it will be seen that one portion of the strip comprises a base 10, and another portion forms the top 11, the base and top being connected by end sections 12, and 13, all of these portions being integral and formed of one strip of metal. One end of the strip is bent to form a lip 14, which is interlocked with the other extreme end of the strip which forms the base 10, as clearly shown in Fig. 2. A portion of the base section 10, is punched or drawn, or otherwise formed into a tubular rivet 15, by means of which the device as a whole is to be attached to the shoe or other article.

Near the end of the section 12, the base and top sections are formed with bearings for the trunnions of the roller 16. As shown in Fig. 2, these bearings may comprise circular openings which receive circular studs at the ends of the roller. As shown in Fig. 3, one end of the roller may have the trunnion entering an orifice in the base section 10, and at the other end a socket in the roller receiving a stud bearing pressed downward from the top section 11. Or, as shown in Fig. 4, both ends of the roller 16 may have socket depressions receiving stud 80 bearings pressed inward from the base and top sections of the housing.

In the forms shown in Figs. 3 and 4, the bearing in the top section 11 presents a depression in the upper surface of that section which receives some of the enamel or other coating. Therefore this top bearing becomes at the same time a trunnion and a retaining holder for the coating.

Instead of forming a locking lip 14 at one end of the strip, the strip may be made longer, as shown in Figs. 6, 7 and 8 to form a plate 141, extending under the base 10, said plate being formed with an opening through which the tubular rivet 15 extends. This projection of the rivet through the opening of the plate section 141, locks the ends of the strip. Whether the device be formed as in Fig. 2, or as shown in Figs. 6, or 7, the ends of the strip are firmly locked so that there can be no such separation or spread of the housing as would permit the roller to slip from its bearings. And in both forms, the sides of the housing are entirely open so that the lacing, whether pro- 110

vided with a metal tip or not, can readily be passed through the device so that in use the strain and wear of the lacing will be taken up by the roller.

5 The top section 11 of the strip may be, when stamped out, somewhat wider than the other portions, to be turned over to form lips 17; these lips may be corrugated or serrated and may be formed with perforations, as shown in Figs. 1, 2, and 5, so that enamel or other coating applied to the device will be anchored immovably, and held so that it will not chip off.

10 The device when complete and applied to a shoe is in a manner similar to the ordinary lacing hooks and saves the wear on the lacing by reducing the friction. Moreover, there can be no catching upon any projecting portions, such as might either tear 15 the lacing or fabric coming in contact with the device. It therefore constitutes a suitable lacing-holder for women's shoes as well as men's, especially, since the wide side 20 openings enable wide lacings to pass 25 through, as well as narrow ones.

The lacing device as a whole comprises a single strip of metal having integral attaching means near one end and an opening near the other end, the strip being bent to form 30 an elongated housing, the attaching means passing through said opening and thereby interlocking the ends of the strip so as to preserve the elongated form of the housing and insure the provision of a space through 35 which the lacing can be passed above the attaching means, the roller 16 being at the other end of the housing or out of alinement with the attaching means. Moreover, when the strip is made as shown in Figs. 6 and 8, 40 with the end extending under substantially the entire length of the base portion of the housing, said base portion is not only stiffened thereby, but the lower trunnion or bearing of the roller is prevented from 45 coming in contact with the surface of the material to which the device is to be secured. In other words, the extension or portion 141 of the strip provides a smooth 50 under surface of the housing to bear on the leather or other material.

Having now described my invention, what I claim is:

1. A lacing device comprising a housing formed of a single strip of material having

55 a top portion, end portions and a double-thick base, the upper layer of the base having an opening, a roller having a trunnion in said opening and having its upper end rotatively engaged with the top of the housing, the under layer of the base extending 60 under the said roller trunnion and preventing contact of said trunnion with the material to which the device is attached.

2. A lacing device formed of a single strip of metal having integral attaching 65 means near one end and an opening near the other end, said strip being bent to form an elongated housing and having said attaching means passing through said opening whereby the ends of the strip are interlocked, and a roller mounted in said housing 70 out of alinement with the attaching means, the space in the housing above the attaching means providing room for the insertion of a lacing, the end of the strip which has 75 the opening extending under practically the entire length of the base portion of the housing and forming a double-thick base to stiffen said base and to provide a smooth under surface to bear on the material to 80 which the device is to be secured.

3. A lacing device comprising a strip of metal bent to form an elongated housing, and a roller mounted therein, the bearing for the upper end of the roller comprising 85 a socket or depression in the roller and a hollow stud projecting into said socket or depression from the housing whereby the bearing for the upper end of the roller becomes at the same time a trunnion and a 90 retaining holder for a suitable coating, the strip forming the housing having attaching means located at one side of the axis of the roller.

4. A lacing device comprising an elongated box-shaped housing, the top section having its edge portions turned over and inwardly above and substantially parallel with the main portion of the top section, whereby the edges of said top section are of 100 double thickness.

In testimony whereof I have affixed my signature, in presence of two witnesses.

JOHN WESLEY BARBER.
